UNITED STATES PATENT OFFICE.

OSCAR LOEWENBACH, OF MILWAUKEE, WISCONSIN.

DETACHABLE COVER FOR PADS, BOOKS, &c.

964,668.

Specification of Letters Patent. Patented July 19, 1910.

Application filed March 5, 1910. Serial No. 547,439.

To all whom it may concern:

Be it known that I, OSCAR LOEWENBACH, a citizen of the United States, residing at Milwaukee, county of Milwaukee, and State 5 of Wisconsin, have invented new and useful Improvements in Detachable Covers for Pads, Books, &c., of which the following is a specification.

My invention relates to improvements in 10 detachable covers for pads, books, etc.

The object of my invention is to provide a form of cover, which, when applied to a pad, may be opened and closed with or without the leaves of the pad without causing 15 the fastenings to release.

A further object of my invention is to provide a form of construction in which the cover may be repeatedly used, regard being had for simplicity and cheapness of 20 construction, as well as for durability.

A further object of my invention is to provide a form of construction in which pads of various thicknesses may be secured and firmly held in position against one of 25 the covers.

In the following description reference is had to the accompanying drawings, in which—

Figure 1 is a perspective view showing 30 my invention applied to a pad, the latter being illustrated as partially removed from the cover, and the fastenings being shown in releasing position. Fig. 2 is a sectional view drawn longitudinally through the pad 35 and its covers and on a line exposing one of the fastening posts. Fig. 3 is a cross sectional view drawn through the pad and its covers in front of the posts.

Like parts are identified by the same reference characters throughout the several views.

A and B are the respective covers, the outer surfaces of which are preferably formed of leather.

C is a binding, which is rigidly secured to the cover A but is unattached to the back D and cover B. The binding C is formed of a plurality of layers of any suitable material, such as fabric or leather, and has embedded therein a metallic plate E located between the layers and held in position by said layers and by eyelet fastenings F. Another metallic plate G is mounted upon that portion of the backing C which is secured 55 to the cover A, and is provided with out-

wardly projecting posts H, the extremities of said posts being provided with heads I connected with the rest of the posts by neck portions J. The cover A is preferably provided with an inner covering a, which conceals the metallic plate G and also holds it in position upon the outer portion of the cover A, the binding C being partially interposed between the parts G and A as above explained.

The eyelets F are formed of spring metal and are adapted to engage the heads I of the posts H and to secure the binding C to the posts by the expansion of the eyelet metal into the neck portions J of the posts. 70 These posts H and eyelets F are not claimed as my invention, except in so far as they enter into combination with the other parts of my improved cover.

The binding C is flexible and is of sufficient size to lap over the largest book, pad or block K through which the heads of the posts are adapted to project. The binding is unconnected with the cover B, except by means of the flexible back D and cover A. 75 The covers A and B may be either flexible or inflexible, but the back D should have additional flexibility. It is obvious that when the cover B is swung downwardly it will not pull the eyelet fastenings F from the posts H, but will leave the pad or book securely bound to the cover A. The eyelet fastenings F, however, are so formed that they can be easily detached from the posts by pulling upon the binding C adjacent to 80 the fastenings.

Where the pad K' is of less thickness than the length of the posts H between the plate G and the necks J, it is held in position by the spring L. This spring is riveted to the binding at M, the rivet passing through the metallic plate E. This spring is preferably centrally secured to the plate E and binding and is provided with end portions which normally extend diagonally inwardly toward the cover A, and are provided with outwardly turned extremities N so that the spring will not mar or injure the surface of any pad or book which may be inserted in the binding. This spring L preferably has sufficient flexibility to permit it to assume a substantially flat position where the pad equals in thickness the full capacity of the posts to receive it.

Having thus described my invention, what 110

I claim as new, and desire to secure by Letters Patent, is,—

1. The combination of a pair of covers connected with each other by a relatively 5 flexible back, of a pair of posts, rigidly mounted upon the inner face of one of the covers near the back, and a flexible binding secured to said cover at the back and extending from one post to the other and 10 provided with fastenings adapted to engage the free ends of the posts, said binding being otherwise unconnected with the back and unconnected with the other cover.

2. The combination of a pair of covers, a 15 flexible back connecting said covers, a metallic plate mounted upon the inner face of one of said covers near the back, a pair of posts mounted upon said metallic plate, and a flexible non-metallic binding permanently 20 secured to said posts and cover at the attached ends of said posts, and provided with fastenings adapted to detachably engage the other ends of said posts when the binding is in position for use; said binding being 25 otherwise unconnected with either the covers or the back.

3. The combination of a pair of covers, a flexible back connecting said covers, a pair

of posts mounted upon the inner face of one of the covers near the back, a flexible 30 non-metallic binding also mounted upon said cover and provided with fastenings adapted to resiliently engage the free ends of the posts, and a metallic reinforcing bar mounted in said flexible binding and connected with said fastenings; said binding being otherwise unconnected with either the covers or the back.

4. The combination of a pair of covers, a flexible back connecting said covers, posts 40 mounted upon the inner face of one of the covers, a flexible binding connected with said cover and adapted to resiliently engage the free ends of the posts, and a spring connected with said flexible binding and adapted to bear upon the surface of a pad when the latter is mounted upon the posts and the post supporting cover, with the flexible binding engaging the free ends of the posts.

In testimony whereof I affix my signature 50 in the presence of two witnesses.

OSCAR LOEWENBACH.
